D. DEWEY.
SHEARING MACHINE.

Patented Dec. 7, 1814.

David Dewey.

Letters Patent.

The schedule referred to in these Letters Patent and making part of the same, containing a description in the words of the said David Dewey himself of his vibrating Shearing Machine.

This machine consists of an oblong frame, within which is a bushion-like enclosure by cottoners to shear upon with hand shears and the cloth is spread and tucked upon the bushion in the same manner as that it were to be sheared with hand shears. The shears are about two feet long and are fixed in a frame of about two and a half feet square, with one girth bent from the frame and parallel with one side of the frame. The under blade of the shears is horizontal and is secured on upon the under side of a girth that extends from the girth first mentioned to the parallel and farthermost side of the frame. The fly or vibrating blade is suspended over the under blade by pivot at each end and is pressed down upon the under blade by springs upon each pivot except at a point quite through the first mentioned girth. It is one and a half inches wide and twisted irregularly and half round and is ground only on one edge. It vibrates by the person turning a wheel suspended in the first mentioned girth near the nearest parallel side of the frame. The wheel with a band turns a wheel upon a crank suspended like the wheel. The crank contains four right angles and turns a stanch from the middle of the crank to a nose of about two inches long which is fastened to the end of the fly or to the pivot that extends through the girth as aforesaid. The band, the pitman and the aforesaid fly blade a vibrating motion. This frame is placed upon the first mentioned frame or ways and moves upon a piece of the blot at any width by means of a worm or spire upon the wheel aforesaid which matches and moves a bog wheel suspended on a perpendicular pin. There is a small cog wheel on the lower end of this pin which matches with pins or teeth fixed in the ways the operation is by turning the wheel aforesaid.

Drawing

approached by a hand. The performances of persons may be
upheld in such cases the small cog-wheel is sent from the upper part
and the upper part may be moved back by hand to its former
place.
